UNITED STATES PATENT OFFICE.

HENRY RALPH KELLERMAN, OF SYDNEY, NEW SOUTH WALES, AUSTRALIA,
ASSIGNOR OF ONE-HALF TO HENRY PETRIE FLETCHER, OF SYDNEY, NEW
SOUTH WALES, AUSTRALIA.

LATCH FOR DOORS, GATES, AND THE LIKE.

1,350,258.

Specification of Letters Patent. Patented Aug. 17, 1920.

Application filed January 28, 1919. Serial No. 273,632.

To all whom it may concern:

Be it known that I, HENRY RALPH KELLERMAN, a subject of the King of Great Britain, residing at 30 Heeley street, Paddington, Sydney, in the State of New South Wales, Commonwealth of Australia, have invented new and useful Improvements in Latches for Doors, Gates, and the like of which the following is a specification.

This invention relates to latches for doors, gates and the like and has been devised to provide a latch having a detachable operative lever which can be readily withdrawn from one side of the latch and inserted in the opposite side thereof, thereby rendering the latch suitable for application to either a right-hand or a left-hand door or gate as may be required.

The invention is particularly adapted for use on the doors of motor cars and like vehicles, in which latch bolts are operated by levers extending upwardly within the doors and projecting outwardly from slots formed in the top thereof. The latches commonly used for this purpose are made and sold ordinarily in pairs, one being suitable only for a right-hand door and the other only for a left-hand door.

By providing a latch suitable for either a near or an off-side door manufacture is according to the invention greatly simplified as only one pattern need be made and the cost of the articles is thereby reduced.

The invention also furnishes means whereby, in the event of a door being slammed, the operative lever is not forcibly moved in the slot at the top of the door. The risk of injury to a person's fingers attendant on the use of latches of ordinary type is thereby avoided.

The invention when being applied to a door requires the removal of only a small amount of the woodwork, and when fixed thereon will be found durable and secure.

According to the invention there is provided in a door or gate latch a spring controlled latch bolt slidably movable in guides on a base plate, fulcrum pins in the base plate on opposite sides of said bolt, a reversible lever for manual operation of the latch bolt which is capable of detachable connection with either of the fulcrum pins to adapt the latch to a right-hand or a left-hand door, and means for retaining said

lever in position. Means are provided for rigidly holding the operating lever when the same is out of use, thereby preventing any tendency of the latter to rattle.

In order that the invention may be readily understood reference is made to the accompanying drawings illustrating the invention in preferred constructions and wherein:

Figure 1 is a view in side elevation.

Fig. 2 is a longitudinal section on the line 2—2 Fig. 1. 65

Fig. 3 illustrates in side elevation a modification.

Fig. 4 is a transverse section on the line 4—4 Fig. 3.

Fig. 5 illustrates in side elevation a further modification.

The numeral 1 designates a base plate made of suitable metal of required thickness or gage and provided at its front end with a flange or laterally bent portion 2 preferably formed integrally therewith. In the flange 2 is formed a centrally disposed opening or hole 3, in which slidably fits a latch bolt 4 having at its rearward end and preferably integral therewith a cross-piece 5. 75

Parallelly disposed stems 6 rigidly secured to said cross-piece 5 extend rearwardly therefrom and are guided in holes 7 formed in the flange 8 of an angle plate 9 which is detachably fixed by screws 10 to said base plate 1. 85

Springs 11, mounted upon said stems 6, are interposed between said cross-piece 5 and the flange 8 of said angle plate 9. This flange forms a fixed abutment against which the rearward ends of said springs 11 bear, while the forward ends of the latter exert pressure upon the cross-piece 5 which tends to urge the latch bolt 4 outwardly from the flange 2. 95

Pins 12 having enlarged beads 13 are securely fixed in the base plate 1 on opposite sides of and at suitable equal distances from said latch bolt 4. Either of these pins 12 is adapted to form a fulcrum or pivot for an operative lever as 14.

This lever 14 is located in front of the cross-piece 5 and is passed through a recess or opening 15 formed in the latch bolt 4. 105 This recess 15 is made of greater width than the lever 14. By this means the bolt 4 is rendered capable of movement independ-

ently of said lever 14. The end of said lever 14 is provided with a longitudinal slot 16 which engages with one of the pins 12 which forms a fulcrum or pivot for said lever, and the rearward edge of the latter contacts with the front of said cross-piece 5.

If pressure be applied in a rearward direction to the lever 14 the latter will bear upon the cross-piece 5 on the end thereof remote from the fulcrum pin 12 upon which said lever 14 is pivoted. The cross-piece 5 is moved rearwardly in opposition to the springs 11 and the latch bolt 4 is drawn inwardly through the opening 3, thereby releasing a door to which the latch is affixed.

In order to prevent endwise movement of the lever 14, which might effect a disengagement of the slot 16 from the pin 12, said lever 14 is provided with a rearwardly extending tongue or lug 17 which fits freely into a slotted opening 18 formed transversely in said cross-piece 5.

If it is required to convert the latch to suit a right-hand or a left-hand door as the case may be, pressure is applied to the cross-piece 5 or to the latch bolt 4 in a rearward endwise direction, thereby compressing said springs 11. When the cross-piece 5 has been pushed inwardly for a sufficient distance the tongue 17 will clear said slotted opening 18, thereby permitting the lever 14 to be drawn endwise out of the latch. Said lever 14 is now reversed or turned over, inserted in the opposite side of the latch and moved into the position indicated by broken lines in Fig. 1 with the slot 16 in engagement with the opposite fulcrum pin 12.

The latch is now ready for application to a door which opens in the opposite direction to a door for which said latch was suitable before the lever 14 was withdrawn.

Normally when the latch bolt 4 is in its outermost or engaged position, the cross-piece 5 under the action of the spring 11 holds the forward edge of the lever 14 in contact with the pin 12 and beneath the head 13 thereof. Said pin 12 limits the outward movements of the latch bolt 4 and at the same time effectively prevents rattling of said lever 14. For the latter purpose also said cross-piece 5 can be recessed or undercut as at 19. It will be understood that one of said pins 12 forms the fulcrum of the lever 14, while the opposite pin 12 forms a stop for said lever and latch bolt.

It will be observed that the cross-piece 5 is free to move inwardly without taking with it the lever 14. Therefore, there is removed the risk, due to slamming of a door, of a person's fingers becoming jammed between said lever 14 and the end of the slot in a door, which jamming is apt to occur with latches wherein the operative levers are pivotally connected to the latch bolts.

In assembling the latch, the latch bolt 4 is

inserted through the opening 3 from the inner side thereof. The springs 11 are then slipped over the stems 6 and the angle plate 9 is fixed in position with said stems extending through the holes 7. The lever 14 is then placed in position on the required side of the latch, as hereinbefore described.

In the modifications of the invention illustrated in Figs. 3 to 5, the cross-piece 5 is eliminated and said latch bolt 4 is provided with a rearwardly extending stem 6. The rearward end of this stem passes through a hole 7^a made through a lug 8^a formed integrally with said base plate 1. A spring 11 is mounted upon said stem 6 being interposed between the end of said latch bolt 4 and the lug 8^a.

The latch bolt 4 can be arranged centrally on the base plate 1 as is shown in Fig. 5 or it may be located to one side of the center line thereof as is shown in Fig. 3.

Said latch bolt 4 is provided with a recess or opening 15 and the rearward end of the latter is rounded to form a cam face 20 against which the rearward side of the operating lever 14 is adapted to bear.

The base plate 1 is provided with alternative headed fulcrum pins 12 and said lever 14 is capable of insertion into the latch from either side to render the latter capable of application to a right-hand or a left-hand door as required.

In the arrangement shown in Fig. 3, the distance between the fulcrum pin 12 and the cam face 20 can be increased without unduly increasing the width of said base plate 1, thereby reducing the length of the arc through which it is necessary to move the upper end of said lever 14 when operating the latch bolt 4. For this purpose duplicate openings 3 and holes 7^a are formed in said flange 2 and lug 8^a, respectively, on opposite sides of the longitudinal center line of said base plate 1, and at equal distances therefrom. Said latch bolt 4 and stem 6 can be placed in either of said openings 3 and holes 7^a, as may be required.

In order to prevent accidental endwise displacement of said operating lever 14 and consequent disengagement of the same from its fulcrum pin 12, the end thereof is provided with a rounded longitudinal slot 21 adapted to fit said pin 12.

The rounded slot 21 is furnished with a narrow entrance 22 while the slotted end of said lever 14 is spring tempered. By this means the sides of said slot 21 are enabled to spring apart when said lever 14 is being engaged with or disengaged from said fulcrum pin 12. When the pin 12 is in position in said slot 21 considerable endwise force is required to dislodge the lever 14 from position.

In an alternative arrangement for preventing accidental displacement of said lever 130

14 the same is provided with a laterally formed slot 23 adapted to engage said pin 12 in lieu of slots 16 and 21, as hereinbefore described—see Fig. 5.

5 In order to withdraw said lever 14 when so constructed, the upper end thereof is pushed forwardly and its front edge pivots upon the upper fulcrum pin 12. The latch bolt 4 is moved inwardly and the lower end 10 of the lever 14 moves backwardly from the lower fulcrum pin 12. When said slot 23 has cleared the pin 12 the lever 14 is pulled out laterally as before described.

For many purposes it is desirable that the 15 latch bolt 4 should be capable of operation by a movement of the operating lever 14 either to the right or left of its normal upright position.

A second lateral slot 24 can be provided 20 in said lever 14 at a distance above the slot 23 equal to the distance between said fulcrum pins 12. The latch bolt will then be withdrawn, if the lever 14 be moved either backwardly or forwardly, the pins 12 forming alternate fulcrums for the opposed movements.

When the lever 14 is drawn rearwardly the lower fulcrum pin 12 will be the operative one, and said lever 14 will be of the 30 second order, while if said lever 14 be pulled forwardly it will be of the first order and the upper pin 12 will be in operation.

When the latch bolt 4 is in its locked position both slots 23 and 24 are engaged with 35 their respective pins 12, and are held in position beneath the heads 13 thereof. It will be observed that in the normal locked position both pins 12 form in association a stop which limits the forward movement of said 40 lever 14. This arrangement will be found most effective for preventing rattling of said lever 14 which is apt to be caused by vibration when the latch is applied to the door of a motor car or other vehicle.

45 To insert or withdraw a lever 14 so made, the latch bolt 4 is pushed inwardly for a sufficient distance to allow said slots 23 and 24 to clear the respective pins 12.

What I do claim is:—

50 1. A reversible lock for vehicle doors having a base plate, guides on the opposite ends of the base plate, a latch bolt mounted in said guides, a spring for actuating the latch bolt, alternative fulcrum pins fixed in the 55 base plate and positioned on opposite sides of the latch bolt, a detachable and reversible lever for releasing the latch bolt and adapted for insertion into either side of the lock for pivotal engagement with one of said

pins and having its motion limited by the 60 opposite pin.

2. A reversible lock for vehicle doors, having a base plate, a flange at one end of said base plate, an angle plate detachably fitted to the opposite end of said base plate, 65 an opening in said flange, holes in said angle plate, a latch bolt slidably fitting said opening, a cross piece on said latch bolt, stems fixed to the cross piece and fitting said holes, springs on said stems, alternative 70 fulcrum pins fixed in said base plate and positioned on opposite sides of said latch bolt, a slotted operative lever capable of insertion into either side of the lock for pivotal engagement with one of said fulcrum pins, said lever having its motion limited by the opposite fulcrum pin, and means for preventing endwise displacement of said lever. 75

3. A reversible lock for vehicle doors, 80 having a base plate, a flange at one end of the base plate, a lug on the opposite end of said base plate, an opening in said flange, a hole formed in the lug and in alinement with said opening, a latch bolt slidably fitting said opening, a stem on said latch bolt fitting said hole, a spring on said stem, a recess in said latch bolt, a cam face in said recess, an operative lever capable of insertion from either side of the lock into said 90 recess, headed pins fixed in the base plate, and positioned on opposite sides of and equally distant from said latch bolt, and lateral slots formed in said lever and fitting said pins, either pin forming a fulcrum for 95 said lever, and both pins in association providing a stop for said lever.

4. A reversible lock for vehicle doors having a base plate, flanges on the opposite ends of said base plate, duplicate openings in one 100 of the flanges, duplicate holes formed in the opposite flange and in alinement with said openings, a latch bolt slidably fitting either opening, a stem formed on said latch bolt and slidably fitting either hole, a spring on 105 said stem, a recess in said latch bolt, a cam face in said recess, an operative lever capable of insertion from either side of the lock into said recess, alternative fulcrum and stop pins for said lever, and a slotted spring 110 end on said lever.

In testimony whereof I affix my signature in presence of two witnesses.

HENRY RALPH KELLERMAN.
